UNITED STATES PATENT OFFICE.

SAMUEL F. LEAKE, OF PHILADELPHIA, PENNSYLVANIA.

CARRIER FOR PNEUMATIC DISPATCH-TUBES.

SPECIFICATION forming part of Letters Patent No. 431,901, dated July 8, 1890.

Application filed October 26, 1889. Serial No. 328,244. (No model.)

To all whom it may concern:

Be it known that I, SAMUEL F. LEAKE, a citizen of the United States, residing at Philadelphia, in the county of Philadelphia and State of Pennsylvania, have invented certain new and useful Improvements in Carriers for Pneumatic Dispatch-Tube Systems, of which the following is a specification.

My invention has relation to closed tubular or cylindrical carriers for pneumatic dispatch-tubes of the form composed of sections united by yielding or flexible joints; and it has for its object simplicity of construction of parts, and to so construct the outside wall of the carrier that the friction between the carrier and wall is diminished to obtain increased speed of carrier with a given amount of power.

My invention accordingly consists of the combinations, constructions, and arrangements of parts, as hereinafter described in the specification, and pointed out in the claims.

Reference is had to the accompanying drawings, wherein—

Figure 1 represents an elevation of a carrier composed of jointed or yielding sections embodying my invention. Fig. 2 is an elevation of part of the carrier, showing a modified form of joint between the sections. Fig. 3 is a sectional view showing a ball-and-socket joint between the carrier-sections. Fig. 4 is a sectional elevation showing a modified form of gimbal-joint connection between the carrier-sections. Fig. 5 is a transverse section of the joint shown in Fig. 4, said section being taken on the dotted line xx , Fig. 4. Fig. 6 is an elevation showing a spiral spring-joint between the carrier-sections. Fig. 7 is a transverse section of a carrier-section, showing anti-friction coverings or outer surfaces for the carrier-sections. Fig. 8 is a side elevation of same; and Fig. 9 is a view similar to Fig. 7, showing a modification of arrangement or construction of anti-friction outer surfaces for the carrier-sections.

A represents the carrier, which is preferably of a cylindrical form, and is composed of a number of rigid sections $a a' a'' a'''$ connected by flexible or yielding joints or connections B, which may be of any desired or suitable character. Thus, for instance, they may consist of rubber, canvas, cloth, or like connections riveted, as shown at b, to the ap-

proaching ends of succeeding carrier-sections $a a'$, as illustrated in Fig. 1, and said yielding or flexible material may be plain or straight, as indicated in said figure, or it may be of bellows or accordion form, as shown in Fig. 2, in which case it permits of a considerable extension of the carrier, if desired. Instead of riveting said flexible or yielding connections B to the carrier-sections, any other suitable or desired fastenings may be substituted. This described form of rigid sections $a a' a'' a'''$, separate from each other and united by the flexible connections B, is that which I prefer to use, as such connections form part of the body of the carrier. In Fig. 3 the yielding or flexible connection B is in the form of a hollow ball-and-socket joint, and in Figs. 4 and 5 in the form of a gimbal joint, and in Fig. 6 in the form of a spiral spring. Whatever the character of the construction of the joints B may be, the sections a of the carrier are rigid, and the preferable form of joint B used is that which admits of a single apartment carrier from end to end. The rigid sections a impart the necessary stability to the carrier to prevent telescoping or compression of the carrier on itself in case of collision with another carrier or fixture in a tube—as, for instance, a misplaced carrier-switch of a pneumatic dispatch system in which the carrier is used.

The carrier or its sections are preferably covered from end to end with anti-friction material of any suitable kind. This anti-friction material may preferably consist of a compound of asbestos and plumbago or phosphor-bronze or like material and be of a semi-cylindrical form for the lower half of the carrier, as indicated at C, Figs. 7 and 8, so that part of the carrier which imposes its greatest weight directly on the tube and at which is the most friction, has the anti-friction material, while the upper half of the carrier, whereat there is the less friction, may be covered with leather or suitable material D. If desired, however, said anti-friction material C may extend entirely around the carrier as well as from end to end of the same, as indicated in Fig. 9. This feature of the anti-friction material, extending from end to end of the carrier, may be applied to the usual carriers in one piece or section, as well as to those com-

posed of sections. The anti-friction covering distributes the wear of the carrier on its under side from end to end of the same. The carrier is therefore more durable and does not in 5 use unduly wear on any one side to provide space or spaces between it and the tube of the pneumatic system in which it is used for the air exhaust or pressure to race by the carrier without imposing upon the latter its full 10 force or power.

If desired, the carrier may be provided with end supporting-wheels, as shown, described, and claimed in a separate pending 15 application filed by me of an even date here- with, Serial No. 328,243.

I am aware that trains of cars or separate carriers coupled together have been used in pneumatic dispatch-tube systems, and the same are to be distinguished from my sectional carrier in that it is a single carrier. Furthermore, I am aware that anti-frictional 20 rings or washers have been placed on carriers; but such washers are to be distinguished from my anti-frictional carrier or carrier-sections 25 in that the washers concentrate the wear of the same, so that they rapidly or unduly wear to leave spaces between them and the tube of the system for racing of the motive power used in the system.

What I claim is—

1. A pneumatic dispatch-tube carrier composed of two or more separate sections united by flexible connections B, which separate the sections and form part of the body of the carrier, substantially as set forth. 30

2. A pneumatic dispatch-tube carrier having a covering of anti-friction material extending from end to end of the carrier section or sections, substantially as set forth. 35

3. A pneumatic dispatch-tube sectional carrier having on the under side of each section anti-frictional material extending from end to end of the same, substantially as set forth. 40

4. A pneumatic dispatch-tube sectional carrier having on the under side of each section a covering or layer of anti-friction material, and on the upper side of each section a covering or layer of different material extending from end to end of the carrier-sections, substantially as set forth. 45

In testimony whereof I affix my signature in presence of two witnesses.

SAMUEL F. LEAKE.
